MEANS FOR SEPARATING MATERIALS

Robert G. Guthrie and Oscar J. Wilbor, Chicago,
Ill., assignors to Chicago By-Products Corporation,
Chicago, Ill., a corporation of Illinois

Application November 15, 1940, Serial No. 365,806.

1 Claim. (Cl. 209—114)

The invention relates to separation of materials having different characteristics, and in its more specific aspects has to do with means for separating certain mineral values contained in an ore from the rock of the ore.

The particular problem which this invention solves is the separation of vermiculite from the accompanying rock formations, largely granite, quartz, or the like.

Vermiculite is a laminated mineral consisting of thin flakes of silicon dioxide with interleaved impurities largely in the form of metallic oxides and containing combined water and moisture.

The flakes or plates of silicon dioxide may be extracted from the ore by a process described in Patent No. 1,898,774, and they then exhibit the property of a highly effective and efficient adsorbent. These finished adsorbent silica flakes are termed "Lamisilite."

In the process of producing Lamisilite, the rock containing the ore is mined to free it as largely as possible from the accompanying impurities consisting chiefly of granite, quartz, and similar stone. The ore with an unavoidable percentage of rock is crushed to the desired size, which, in a particular instance, is in irregular particles of a major dimension of from 0.5" to 0.75". The size may vary over a considerable range. If smaller flakes are desired, the size of the crushed ore is reduced accordingly. The process and machine of our invention operate upon a principle which makes size of no importance.

Since the ore is a relatively soft, laminated mineral, it breaks into more or less flat-sided particles of irregular outline. The accompanying stone breaks into particles which have more nearly the same diameter in all directions.

We have observed that the particles of vermiculite ore, when allowed freedom to do so, will come to rest upon a flat face. The particles of stone having no pronounced planes of cleavage will generally be found to approximate the shape of pebbles, i. e., more nearly spherical, and are less stably supported on a flat surface. The flat-sided particles of vermiculite have a wide base and lower center of gravity than have the particles of stone, when both will pass the same size screen.

We take advantage of the observed characteristics of the two kinds of materials to secure a separation by disposing the two materials, in the form of a mixture, upon an inclined plane and imparting a limited amount of kinetic energy to the particles of the mixture. The particles with flat sides, i. e., the laminated ore, will find

greater difficulty in descending the incline than will the more nearly rounded particles of stone. Hence, the particles of stone will run off first. This property of the particles of stone running ahead of the particles of vermiculite is present, even if the particles of stone should, by virtue of conchoidal fracture, assume the approximate shape of tetrahedrons. The stone particles would, nevertheless, for the same screen size, carry the center of gravity higher above the supporting plane than would parallel-sided particles of laminated material. Therefore, we have found that by imparting kinetic energy to the mixed particles on an inclined plane, the particles of stone will in general travel downward faster than will the particles of laminated material.

This same method of separation may be employed for separating and/or classifying any similar mixture, of two or more types of particles having differences in effective area of base for the same mass, or differences in effective height of center of gravity for the same mass. We have observed, in a loose way of speaking, that the particles of stone have a greater "rollability" than the particles of vermiculite, even with fairly wide difference in screen diameter and, therefore, the particles of stone can be caused to roll off an inclined plane and the vermiculite particles be retained upon it, when the particles are livened up by imparting kinetic energy to them.

In order to make the process continuous, we have provided a table with a travelling surface such as a conveyor belt. The moving surface travels in a direction opposite to the travel of the particles. By regulating the inclination of the surface, the kinetic energy input to the particles and the negative travel of the table, a combination of actions is readily obtained when the particles of vermiculite travel backward while the particles of stone travel forward, relative to a fixed point on the table. Hence, the two types of particles are caused to travel in opposite directions, which is an ideal condition for separation.

The mixture of materials to be separated may be treated either wet or dry. In the wet treatment sufficient water is added to coat with moisture the particles of material. Wetting of the mixture tends to cause the particles of vermiculite to adhere to the supporting surface, due to the flatness of such particles and their relatively large area of contact with the supporting surface, whereas the particles of rock, due to their roughness and relatively small area of contact with the supporting surface, have relatively little

tendency to adhere thereto. The wet mixture is then subjected to treatment in the manner above outlined, for separating the rock particles from the vermiculite, such separation being facilitated by the moistened condition of the mixture.

In producing the highly adsorbent silica flakes, known as "Lamisilite," it is important that the rock content be kept at a minimum. If it be assumed that after separation but 5% rock remains, we would then have a mixture of 95% vermiculite and 5% rock, such as granite or quartz, insoluble in sulphuric acid. This mixture, to produce the adsorbent silica flakes referred to, is leached in sulphuric acid. Approximately 56% of the vermiculite is removed, in the form of acid soluble impurities, during the leaching operation, producing silica flakes in amount equal to 41.8% of the original 95% of vermiculite. But the residue also includes the original 5% of acid insoluble rock and is equal to 46.8% of the original 100% of mixture comprising 95% vermiculite and 5% rock. Accordingly, in the residue after leaching we have a mixture of 89.32 parts silica flakes, known as "Lamisilite," and 10.68 parts rock. Assuming pure "Lamisilite" to have an adsorptive power for water of 20% of its own weight, a mixture of 89.32% "Lamisilite" and 10.68% rock will adsorb but 17.86% of its weight in water.

It is thus apparent that the presence of but 5% of rock in the vermiculite is objectionable, particularly in commercial operations in which large quantities of the adsorbent silica flakes are used and where maximum power of adsorption is important. In hand picking the rock particles from the vermiculite ore, as is the present practice, about 5% of rock cannot be removed, due to the mechanical treatment which the ore receives at the mine. This rock remains in the vermiculite and the efficiency of the final product, in practice, is reduced. While it is possible, by hand picking, to reduce the rock content to as low as approximately 5%, that requires great care and considerable time. For that reason, hand picking is not practicable from the commercial standpoint and would render the cost of the final product prohibitive. By our method above outlined it is possible to separate the particles of rock from the vermiculite much faster than by hand picking and so efficiently that practically no rock is present in the separated vermiculite, which is conducive to the production of substantially pure adsorbent silica flakes at materially less cost than is possible when hand picking is employed.

Briefly, our invention is directed to apparatus for separating two materials having different characteristics such that, when a mixture of such materials is placed upon an inclined supporting surface and kinetic energy is transmitted to the particles of the mixture, the particles of one of the materials will travel downward over the inclined supporting surface faster than the particles of the other material, which method utilizes the referred to different characteristics of the materials for effecting separation thereof. Preferably, our apparatus also comprises means for grading or classification of one of the separated materials, for facilitating subsequent treatment thereof. Further objects and advantages of our invention will appear from the detailed description.

The drawing is an isometric side view of a form of apparatus used in practicing the method of our invention.

The apparatus comprises an endless belt 1, of canvas or other suitable material, passed about a lower roll 2 rotatably mounted in a base frame 6, and about an upper roll 3 rotatably mounted in uprights 18, pivoted at their lower ends to frame 6 and held in position for maintaining the belt under proper tension, by means of braces 4. The latter are pivoted at their upper ends to uprights 18 and are adjustably secured at their lower portions to frame 6 by bolt and slot means 5. Belt 1 is thus supported for travel about the rolls 2 and 3, with its upper run disposed at an inclination upward toward one end of frame 6, which end, for purposes of description, may be designated the forward end of the frame. The latter is supported on suitably disposed coil springs 7, 7a, 7b, and 7c, to facilitate vibration of the frame and parts mounted thereon, as will be explained more fully presently.

A pulley 8, secured on the shaft of roll 2, receives a belt 19 which passes about a pulley 9 of a speed reducing unit 10 of known type, disposed adjacent one side of frame 6. Unit 10 is suitably secured, as by bolting, to a platform 20 extending transversely of and welded or otherwise suitably secured to the frame 20. An electric motor 11, bolted or otherwise suitably secured to platform 20, has driving connection to unit 10, by means of a belt 21 passing about a pulley 22 secured on the shaft of motor 11 and about a pulley 23 secured on the drive shaft 24 of unit 10. A second pulley 25 is secured on shaft 24 and receives a belt 26 passing about a pulley 27 secured on a shaft 28, rotatably mounted in a bracket 12 bolted, or otherwise suitably secured, to platform 20 at the transverse center of frame 6. An eccentric weight 29 is secured on shaft 28 for rotation therewith. When the motor 11 is in operation, belt 1 is driven therefrom at relatively low speed, the drive being such that the upper run of the belt travels upward and forward of frame 6, as indicated by the arrow. During travel of belt 1, shaft 28 is driven at relatively high speed and the eccentric weight 29 serves to impart vibration to frame 6 and belt 1, generally transversely thereof. This vibration serves to spread materials deposited upon the upper run of the belt transversely thereof and to impart kinetic energy to the particles of such materials. Also, it will be clear that the upper run of belt 1 is restrained against transverse swinging movement and travels substantially in a fixed plane, and when weight 29 reaches its uppermost position it exerts its maximum effect tending to move frame 6 upward, and when it reaches its lowermost position it exerts its maximum effect tending to move frame 6 downward. The effect of weight 29 is, in each instance, supplemented by the reactions of springs 7, 7a, 7b and 7c. In that manner, the upper run of belt 1 is vibrated vertically, which imparts kinetic energy to the material particles and assists in rapid separation thereof in the manner above explained.

A downwardly and forwardly inclined trough 13 extends from adjacent roll 3 to a forwardly opening hood 14 mounted at the front of frame 6. Trough 13 is disposed to discharge material received thereby downward in front of the opening of hood 14, to which fluid under pressure, conveniently air, is supplied by a conduit 15, from a suitable source (not shown), such as a blower of any suitable known type. A receptacle 16 is disposed adjacent and below hood 14, at the front thereof, and is separated into a plurality of compartments disposed parallel with the opening of

hood 14. As shown, receptacle 16 is divided into two compartments by a partition 17. In practice, however, receptacle 16 may be provided with any suitable number of compartments, depending upon the nature of the material being processed, the force of the fluid or air blast discharged from hood 14 and related factors. It will be clear that when particles of material are discharged from trough 13, the lighter particles will be blown by the air blast to a greater distance than the heavier particles. Accordingly, by properly regulating the air blast for a given material, the smaller particles of that material will be deposited in compartment 16a of receptacle 16 and the larger particles will be deposited in compartment 16b. If three compartments were provided, the smallest particles would be deposited in the outermost compartment, the next smaller particles in the central compartment, and the largest particles in the first or innermost compartment. The material is thus automatically graded or classified according to particle size, and may be separated to as many grades as desired, within limits. That is of importance where the material is to be subjected to treatment the duration of which depends, to a greater or lesser extent, upon the size of the particles of the material, as will appear more fully presently.

The mixture of materials to be separated, such as crushed vermiculite ore comprising particles of rock and particles of vermiculite, is delivered onto the upper run of belt 1 in a suitable manner. Conveniently, a delivery spout 30, which may lead from a storage bin (not shown), is disposed with its lower end a short distance above belt 1, at the lower portion thereof. The ore discharged from spout 30 is spread upon the upper run of belt 1, by the transverse vibration thereof, such vibration, supplemented by the vertical vibration of this run of belt 1, imparting kinetic energy to the particles of rock and vermiculite. Due to the characteristics of the rock particles, previously referred to, they roll down the inclined belt and are discharged from the lower end thereof, whereas the particles of vermiculite, due to their characteristics, tend to remain more or less in repose upon the belt or, if they tend to move downward over the belt travel at much lower speed than the rock particles. The speed of the belt is so regulated as to more than off-set any downward travel thereon of the vermiculite particles while permitting free downward travel of the rock particles. The net result is that, with respect to a fixed point at the lower end of spout 30, the rock particles travel downward over the belt and are discharged from the lower end thereof, whereas the vermiculite particles remain upon the upper run of the belt and travel upward therewith. That will be clear from Figure 1, in which the more or less rounded or pebble-shaped rock particles are indicated by the reference character *r*, and the flat low lying vermiculite particles are indicated by the reference character *v*. It will be understood that, in Figure 1, the particles of both the rock and the vermiculite are exaggerated in size, for purposes of illustration only, and, in practice, these particles would be rather small, having, for example, a major dimension of from .05" to .75". We thus take advantage of the different characteristics of the rock particles and the vermiculite particles to effect substantially complete separation thereof in a highly efficient manner which renders possible handling comparatively large quantities of ore as a continuous

operation, with resulting increase in production and decreased cost.

The separated vermiculite particles *v* are discharged from the upper end of the belt 1 into trough 13, from which they are discharged and automatically graded according to size, in the manner above described. We thus both separate the vermiculite particles from the rock particles and grade or classify the vermiculite particles according to size, in a single continuous operation.

As has been previously explained, the vermiculite particles are leached in sulphuric acid to produce the desired highly adsorbent silica flakes.

We have determined by experience that there is a certain optimum leaching time period for vermiculite, dependent largely upon the size of the particles being treated. In general, if the particles are small, they should be leached for less time than should appreciably large particles. If the optimum leaching time is exceeded, the adsorptive power of the resulting silica flakes will be reduced. It will be seen, therefore, that if a batch of vermiculite particles varying widely in size is leached, either the larger particles will be insufficiently leached or the small particles will be leached for too long a time. The net result is that the silica flakes produced from such a batch will have less adsorptive capacity than would be the case if the particles of the batch to be leached were all of the same size and were leached for the optimum time for that size. By classifying the separated vermiculite particles according to size, in the manner above explained, we render it possible to provide batches of particles of approximately the same size. Each batch may then be leached for the optimum time for the size of the particles of that batch, thus assuring that the resulting silica flakes will have maximum adsorptive capacity, which is of importance for obvious reasons.

While we preferably provide a multi-compartment receptacle for receiving the particles of vermiculite segregated or graded according to size, by the air blast, that is not essential to our invention. If the receptacle be omitted, the vermiculite particles may be permitted to accumulate in adjacent piles, the size of the particles decreasing in accordance with the distance of the respective piles from the hood. Also, a receptacle for the particles of stone discharged from the lower end of the belt is not essential, though preferred, and may be omitted if desired.

It will be understood, as above indicated, that variations may be resorted to without departing from the field and scope of our invention, and we intend to include in this application, in which the preferred form only of our invention have been illustrated and described, by way of example, all such variations as fall within the scope of the appended claim.

We claim:

In means for separating two materials the particles of one of which are of more or less generally rounded shape and the particles of the other of which are of a generally flat shape, a frame, spring means mounting said frame for vertical vibratory movement, an endless belt mounted on said frame having an upwardly travelling upper run extending lengthwise of said frame at an inclination thereto and restrained against lengthwise swinging movement, said belt being of such character that the upper run thereof is smooth and permits free downward travel therealong of the generally rounded particles of said one material while retarding by friction only downward

shaft and thereby imparting vertical vibratory movement to said upper run during the travel of said belt, by means of said weight, effective for imparting kinetic energy to the particles of materials.
